UNITED STATES PATENT OFFICE.

LEON ZAJAC, OF PUNXSUTAWNEY, PENNSYLVANIA, ASSIGNEE OF ONE-HALF TO
MICHAEL MARSZALEK, OF PLUMVILLE, PENNSYLVANIA.

DOOR-LOCK.

1,127,714.

Specification of Letters Patent.

Patented Feb. 9, 1915.

Application filed May 12, 1914. Serial No. 833,062.

To all whom it may concern:

Be it known that I, LEON ZAJAC, a citizen of the United States of America, residing at Punxsutawney, in the county of Jefferson and State of Pennsylvania, have invented certain new and useful Improvements in Door-Locks, of which the following is a specification.

This invention relates to new and useful improvements in door locks.

The primary object of this invention is to provide a door lock having a divided projectable bolt, the locking portions thereof being identical and separately operable from the opposite sides of the door.

A further object is to provide a lock with the bolt formed of complementary parts being rectangular in cross section when united, each part thereof being separately operable for individually locking and unlocking the door and having a catch device for rendering either of the same incapable of operation at will.

A further object is to provide complementary locking bolts separately operable from opposite sides of the door and when projected in the locking position being in contacting engagement with the door latch mechanism and preventing a retraction of the latch by means of the door knob.

Another object is to provide a projectable locking bolt having two complementary parts relatively slidable upon each other and adapted for united reception within the rectangular keeper and furnished with a catch positionable from the door edge to render either one of said parts incapable of operation.

A still further object is to provide in a unitary structure a two part locking bolt, the parts thereof being operable from opposite sides of the door and adapted when locked to prevent the actuation of the door latch and also providing a separately actuated bolt having a permanent turn knob, all of the bolt members being provided with a catch in the edge of the door for rendering the bolts inoperative.

With these general objects in view and others that will appear as the nature of the invention is better understood, the same consists in the novel combination and arrangement of parts hereinafter fully de-

scribed, illustrated in the accompanying drawings and pointed out in the appended claims.

In the drawings forming a part of this application and in which like designating characters refer to corresponding parts throughout the several views: Figure 1 is a side elevation of a door provided with the present invention, the adjacent edge of the door casing with the keeper being shown in section. Fig. 2 is an edge elevation of said portion of the door, the door knobs being broken away. Fig. 3 is a plan view of the lock removed from the door and with the side plate thereof removed, illustrating the complementary locking bolt as released by the catch for actuation by the key and with the parts positioned as illustrated in Figs. 1 and 2. Fig. 4 is a similar view with the key partially rotated with the consequent release of one bolt guard. Fig. 5 is a transverse sectional view taken upon line V—V of Fig. 3. Fig. 6 is a transverse sectional view taken upon line VI—VI of Fig. 3. Fig. 7 is a view similar to Fig. 4 showing the nearest section of the double locking bolt as projected by the key to its locking position. Fig. 8 is a sectional view taken upon line VIII—VIII of Fig. 7. Fig. 9 is a detail sectional view upon line IX—IX of Fig. 7. Fig. 10 is a detail sectional view upon line X—X of Fig. 4 showing the catch as engaging the opposite bolt section from the locked section shown in Fig. 7. Fig. 11 is a perspective view of the inner face of the front plate of the lock detached. Fig. 12 is a perspective view of the door knob actuated spring latch detached. Fig. 13 is a perspective view of the three sided lock casing detached. Fig. 14 is a perspective view of the latch tumbler actuator. Fig. 15 is a perspective view of a guard for one of the complementary bolt sections. Fig. 16 is a perspective view of one of the catch journal plates. Fig. 17 is a perspective view of one of the bolt-guard springs. Fig. 18 is a perspective view of the actuator for the individual lock bolt. Fig. 19 is a perspective view of the inner face of the side plate shown in position in Figs. 3, 4 and 7 of the drawings. Figs. 20 and 21 are perspective views of the two sections of the complementary bolt showing the faces thereof which

are adapted to lie adjacent each other. Fig. 22 is a perspective view of the shiftable catch for the complemental bolt. Fig. 23 is a perspective view of the shiftable catch 5 for the individual locking bolt. Fig. 24 is a perspective view of a retaining clip for the complemental bolt catch. Fig. 25 is a perspective view of the individual locking bolt, and Fig. 26 is a perspective view of the key employed with the lock.

Referring more in detail to the drawings, the invention broadly consists of the lock mechanism secured to a door such as 10 in substantially the usual manner and 15 having a spring latch 11 operable by a knob 12 and a complemental locking bolt 13 operable by a key 14 and an individual locking bolt 15 operable by permanently positioned handles 16, said latch, complemental 20 bolt and individual bolt adapted for reception respectively in sockets 17, 18 and 19 in the adjacent portion of the door casing 20 and through correspondingly positioned openings 21, 22 and 23 respectively provided 25 through the keeper plate 24 secured to said casing, while an escutcheon plate 25 is positioned upon opposite sides of the door in the usual manner.

Complemental bolt.—The bolt 13 consists 30 of two lock portions or bolt sections 26 and 27 of substantially the same form and each having similar end portions 28 in stepped block formation adapted for sliding contact with each other and being rectangular 35 in cross section when taken together and adapted for reception within the rectangular opening 29 of the front plate 30 of the lock casing and by which arrangement either of the sections 26 or 27 may be separately actuated while both of said sections 40 may remain projected therethrough in their locked arrangement.

The lock casing 31 as illustrated in Fig. 18 is formed of three side members having 45 the forward members thereof provided with spaced lugs 32 adapted for the reception therebetween of the posts 33 carried by the inner face of the front plate 30 and retained in position by the locking pins 34, thus 50 forming a rectangular casing. An intermediate support plate 35 is positioned within the casing frame 31 equally spaced between the opposite edges thereof and is provided with U-shaped mounts 36 secured to 55 its opposite faces by means of a pin 37 and adapted for the sliding reception of the body portion 38 of the bolt sections 26 and 27 oppositely arranged for individual sliding movements as best illustrated in Fig. 7. 60 Each of the bolt sections is provided with a tumbler 39 slidably mounted between the respective section and the support 35 and adapted for movement in a plane perpendicular to the line of movement of the bolt 65 sections.

The support 35 is provided with oppositely projecting alining pins 40 adapted to aline with the key-hole slots 41 and 42 in the opposite sides 43 and 44 of the casing, the side 43 being illustrated in position in 70 Figs. 3, 4 and 7, while both of the same are illustrated in section in Figs. 5, 6 and 8.

The tumblers 39 are each provided with a substantially semi-circular opening 45 in which one of the pins 40 is accommodated 75 and having the central socket 46 of the key 47 adapted for fitting upon said pin when the key ward 48 is placed through the adjacent key-hole slot for operating the bolt section.

The key ward 48 is provided with an inner shoulder 49 adapted for engaging the side 50 of the tumbler opening 45 and upon a turning of the key from the position illustrated in Fig. 3 to that shown in Fig. 4 slide 85 the contacted tumbler 39 transversely beneath the overlying bolt section 26 thus moving the lug 51 carried by said plate from its seated position within the end notch 52 of the H-shaped slot 53 of the section to a point 0 in alinement with the contracted middle portion 54 of said slot. With the elements positioned as illustrated in Fig. 4 the key ward 48 then engages the forward side of the substantially V shaped open notch 55 of 95 the bolt section 26 and the lug 51 being in alinement with the slot portion 54, a further movement of the key rotarily projects the bolt section 26 outwardly and positions the opposite end notch 56 of the slot 53 in a position to receive the lug 51. The shoulder 49 of the key ward being at this time released by this movement of the key from the side 50, the double spring 57 exerting an outward lateral tendency to the tumbler 39 105 imparts a return sliding movement to the tumbler thus seating the carried lug 51 within the end notch 56.

It is to be noted that the elements of construction as well as the operation of the bolt 110 section 27 is identical to that just described for the complemental section 26, it being noted that the same or an identical key 47 is adapted to similarly actuate the separate sections from the opposite sides of the door. 115

From the above description, it will be seen that the lug 51 retains the section 26 in either its unlocked or locked position and is shiftable by the key for releasing the section upon a sliding movement imparted to 120 the tumbler 39 while the key is then free to longitudinally reciprocate the bolt section at will.

The support 35 is provided with an end block 58 adjacent the inner edges of the 125 mounts 36 and is provided with a central end socket 59 having the end 60 of the catch shaft 61 journaled therein, while the opposite outer end of said shaft is revolvably mounted in a key hole form of opening 62 130

in the front plate 30. The shaft 61 is provided with a head 63 having a single side projecting lug 64 adapted to be normally positioned in alignment with the support 5 35, as best illustrated in Fig. 8 and in which position both of the bolt sections 26 and 27 are released and are free for actuation by means of the lock key 47. The outer journaled end of the shaft 61 is provided with 10 a rectangular socket 65 adapted for the reception of the end projection 66 of the key and whereby the shaft is rotated for positioning its side lug 64 forwardly of the shoulder 66 of the desired one of the bolt 15 sections. The lug 64 is illustrated in Fig. 10 as positioned in front of the shoulder 66 of the section 27 and in dotted lines in the same view is illustrated the said lug positioned forwardly of the shoulder of the section 26. 20 An indicating finger 67 carried by the outer end of the shaft 61 moves in the flaring portion 68 of the key-hole shaped front plate opening 62 and whereby the position of the engaging lug 64 may be noted. A radial lug 69 also carried by the outer end of the shaft 61 and spaced inwardly from the finger 67 is adapted for forming therewith spaced stops for the reception of the clip 70 secured by a screw 71 to the inner face of 30 the front plate 30, which clip is provided with a semi-circular end notch 72 for journaling the adjacent end portion of the shaft therein. A spring 73 encircles the shaft 61, bearing between the outer shoulder 74 adjacent the lug 69 and the head 63, which head is slidable upon the squared portion 75 of the shaft.

From this description it will be seen that with the lug 64 positioned as illustrated in 40 Fig. 8, either bolt section may be freely actuated but that by turning the shaft 61 by means of the key projection 66, the lug 64 may be positioned to prevent the actuation of either one of the sections which may be 45 desired, while the other section will be freely operated by the key from one side of the door.

Door knob latch.—In connection with the above described complementary bolt 13 there 50 is employed the latch tumbler 11 and its operating mechanism all provided in the same casing and formed of substantially the usual construction. An inwardly projecting bracket 76 upon the casing plate 43 positions the shaft 77 which has the latch tumbler secured to the outer end and projecting through the opening 78 of the front plate while the cross head 79 at the opposite end of the shaft 77 is adapted for retracting the 55 tumbler 11 by means of the tumbler actuator 80, while the encircling spring 81 normally retains the tumbler 11 projected which under normal conditions may be inwardly depressed against the action of the spring 81, 60 but is manually retracted by turning the

actuator 80 through the agency of one of the side knobs 12 upon opposite sides of the door.

The cross head 79 is provided with an angular lateral lug 82 projecting therefrom within the path of the outwardly projecting lugs 83 carried by each of the bolt sections 26 and 27. The latch tumbler 11 being normally projected, the normal position of the lateral lug 82 is such as to be brought in contact with either of the bolt section lugs 83, when such sections are projected. By this arrangement it will be evident that upon a locking of either or both of the bolt sections 26 and 27, the latch tumbler 11 will be securely locked in its projected position and thereby imparting additional locking facilities to the structure.

Unitary bolt structure.—The unitary shiftable bolt 15 is positioned within the lock casing and having its locking outer end slidably positioned within the opening 23 of the front plate. The rear end of the bolt 15 is provided with a longitudinal slot 84 adapted to receive the support plate 35 within the same for slidably positioning the said bolt while a shoulder 85 of said bolt is adapted to abut against the face 86 of the plate 35 when the said bolt 15 is entirely retracted, the end face 87 of the slot 84 at 95 such time contacting the edge 88 of said plate. An actuator 89 is journaled upon a turn shaft 90 through the casing sides, while said shaft is provided on its opposite projecting ends with handles 16 and 100 whereby the actuators 89, one being positioned upon each side of the plate 35, are operatively rotated. The actuators 89 are provided with fingers 91 adapted to engage the teeth 92 of the inner end of the bolt 15 and thereby upon rotation of the shaft 90 to either project or retract the bolt as may be desirable. A catch is provided for the bolt 15 similar to that provided for the complementary bolt 13. A shaft 93 is mounted with its outer end journaled in a perforation 94 of the front plate and having a central rectangular socket 95 adapted for the reception of the key extension 66 and whereby said shaft may be revolved. The 115 inner end of said shaft is provided with a head or disk 96 receivable within a slot 97 of the plate 35 and retained revolubly therein by means of oppositely positioned catch journaling plates 98 secured upon opposite 120 sides of the plate 35 and each having a slot 99 for receiving a portion of the periphery of the head disk 96. A radial lug 100 mounted for turning with the shaft 93 is adapted to enter an open side notch 101 125 upon the adjacent side of the bolt 15 and so positioned as to register therewith when the said bolt 15 is in its unlocked retracted position as illustrated in Fig. 3 of the drawings. The unitary bolt 15 is therefore 130

operable by means of a handle 16 upon either side of the door and the movement thereof by said handles is entirely unrestrained in either direction except when the catch lug 100 is positioned within the bolt notch 101 upon a turning of the shaft 93 through the agency of the key projection 66 inserted in the socket 95 at the edge of the door and which engaging of the catch with the bolt is only possible when said bolt 15 is unlocked and by which agency it is prevented from being locked whenever so desired. It is to be noted that a coil spring 102 encircles the shaft 93 bearing at one end against the lug 100 and at the other end against the inner face of the front plate 30, thus taking up wear and preventing an accidental turning of the shaft 15.

From this detailed description of the entire construction the complete functions and operations of all of the parts will be apparent. The spring latch tumbler 11 is operable in the usual manner by the door knobs 12, but is restrained from retraction by an engagement with elements of either of the two bolt sections of the complementary bolt 13 when locked. The separate sections 26 and 27 may be freely operated from their respective separate sides of the door when the catch indicating finger 67 is vertically positioned and at which time the lug 64 is inoperative but either of said sections 26 or 27 is alone operative when the finger 67 is laterally shifted within the key-hole slot 62 in the edge plate of the door and at which time only the released section is operative and from only one side of the door, while the other section is restrained from operating by the lug 64. The individual bolt 15 when released by its catch lug 100 is freely operable by the handles 16 from either side of the door but is restrained from being operated by either of said handles when the lug 100 is engaged within the bolt notch 101.

While the forms of the invention herein shown and described are what are believed to be preferable embodiments thereof, it is nevertheless to be understood that minor changes may be made in the form, proportion and details of construction without departing from the spirit and scope of the invention as set forth in the appended claims.

What I claim as new is:-

55 1. A device of the class described comprising a lock casing, an intermediate support plate positioned therein in spaced relations with and lying in a parallel plane to the side plates of the casing, separate bolt sections having complementary contacting faces and with portions of said sections positioned upon opposite sides of said plate and provided with H-shaped slots therein and with U-shaped marginal notches, tumblers provided with substantially semi-cir-

cular openings, one of said tumblers being positioned upon opposite sides of the support plate and between the adjacent face of said plate and one of said sections, a projecting lug upon each of said tumblers positioned within the H-shaped slot of the adjacent section, a key, a ward upon said key provided with a shoulder, said shoulder adapted for engaging within the opening of said tumbler for moving the same longitudinally of the casing when the ward is in engagement within said side slot of the section upon a lateral movement of the latter, the said tumbler lug adapted for seating within the end notches of said slot when said section is at the extremities of its movement, a post upon said support plate having a socket in the end thereof, the front plate of said casing having an inverted keyhole shaped opening, a shaft journaled at one end in said socket and having its other end partially rotatable within said plate opening, an indicating finger upon the end of said shaft within said plate opening, said bolt sections provided with shoulders, a longitudinally shiftable lug member mounted upon said shaft and adapted for positioning within the line of movement of one of said bolt section shoulders and means for turning the said shaft.

2. A lock comprising a casing, complementary bolt sections slidably mounted within said casing and each having a side shoulder, a support plate within said casing and positioned between the inner ends of said sections, a post upon said support plate having a socket in the end thereof, the front plate of said casing having an inverted key-hole shaped opening, a shaft journaled at one end in said socket and having its other end partially rotatable within said plate opening, an indicating finger upon the end of said shaft within said plate opening, said bolt sections provided with shoulders, a longitudinally shiftable lug member mounted upon said shaft and adapted for positioning within the line of movement of one of said bolt section shoulders and means for turning the said shaft.

3. A lock comprising a casing, a spring-controlled latch slidably-mounted therein, a sectional bolt slidably-mounted in said casing, a supporting partition arranged within the casing and between the sections of the bolt, said bolt sections adapted to be independently projected, and means for holding the latch in locked projected position when either of the bolt sections are projected.

4. A lock comprising a casing, a sectional bolt slidably-mounted within said casing, a supporting wall arranged within said casing and positioned between the bolt sections, said bolts each provided with a forward shoulder, means controlled from the face edge of the lock casing adapted to be se-

70

lectively positioned in the path of movement of either of the bolts to hold the same in unlocked retracted position, and means for positively holding either of the bolt sections in locked projected position.

5. A lock comprising a casing, a spring-controlled latch slidably-mounted therein, a sectional bolt arranged within said casing, a supporting wall carried by said casing and arranged between the bolt sections and constituting a support therefor, vertically sliding tumblers each disposed between the bolt sections and supporting plate, co-operating means between the bolt sections and tumblers adapted to positively hold the bolt sections in either of their retracted or projected positions.

6. A lock comprising a casing, a supporting plate arranged intermediate the side walls of the casing and positioned centrally thereof, a two-part sliding bolt mounted within said casing and having each section disposed laterally of the supporting plate, means within said casing and operable from the front wall thereof for selectively engaging the forward edges of said bolt sections to hold the same in retracted position, vertically slideable tumblers, means associated with each tumbler and positively engaging the adjacent bolt section to hold the bolt sections in either retracted or projected position, a spring-controlled latch within said casing, and means associated with said latch adapted to be engaged by the bolt sections

when in locked position to hold said latch immovable.

7. A lock comprising a casing, a sectional sliding bolt arranged within said casing, means adapted to selectively engage each of said bolt sections to hold the same in retracted position, and indicating means associated with said last-named means whereby it may be determined which of the bolt sections is locked retracted.

8. A lock comprising a casing, a spring-controlled latch slidably-mounted therein, a supporting plate centrally positioned parallel with the side walls of the casing, a sectional bolt slidably-mounted within said casing and supported on said plate, means for selectively engaging said bolt sections to hold the same in unlocked position, independent means associated with each bolt section adapted to positively hold the same in either retracted or projected position, means for projecting said bolt sections, and means carried by the spring-controlled latch adapted to be engaged by said bolt sections when the same are in projected position to hold the spring latch in locked projected position.

In testimony whereof I affix my signature in presence of two witnesses.

LEON ZAJAC.
